(57) **CLAIM**

The ornamental design for a filter housing with baffle, as shown and described.

DESCRIPTION

FIG. 1 is a front, right, top perspective view of a first version of a filter housing with baffle showing new design;

FIG. 2 is a front view of the invention illustrated in FIG. 1;

FIG. 3 is a rear view of the invention illustrated in FIG. 1;

FIG. 4 is a left side view of the invention illustrated in FIG. 1;

FIG. 5 is a right side view of the invention illustrated in FIG. 1;

FIG. 6 is a top view of the invention illustrated in FIG. 1;

FIG. 7 is a bottom view of the invention illustrated in FIG. 1;

FIG. 8 is a front, right, top perspective view of a second version of a filter housing with baffle showing new design;

FIG. 9 is a front view of the invention illustrated in FIG. 8;

FIG. 10 is a rear view of the invention illustrated in FIG. 8;

FIG. 11 is a left side view of the invention illustrated in FIG. 8;

FIG. 12 is a right side view of the invention illustrated in FIG. 8;

FIG. 13 is a top view of the invention illustrated in FIG. 8;

and,

FIG. 14 is a bottom view of the invention illustrated in FIG. 8.

The broken lines in the drawings depict portions of the filter housing with baffle that form no part of the claimed design.
